Primary Examiner — Zenia I Bennett(74) *Attorney, Agent, or Firm* — Birch, Stewart, Kolasch & Birch, LLP(57) **CLAIM**

We claim the ornamental design for a body dryer, as shown and described.

DESCRIPTION

FIG. 1 is a perspective view of a body dryer showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view showing a state that a front bar is moved up and the wind is discharged from the bar; and, FIG. 9 is a perspective view showing a state that a front bar is moved down and the wind is discharged from the bar. The broken lines in the drawings depicting the arrows are for illustrative purposes only and form no part of the claimed design.
